UNITED STATES PATENT OFFICE.

WILLIAM J. SMITH, OF WATERBURY, CONNECTICUT, ASSIGNOR TO WATERBURY CLOCK
CO., OF WATERBURY, CONNECTICUT, A CORPORATION.

ALARM-CLOCK.

1,332,076.

Specification of Letters Patent. Patented Feb. 24, 1920.

Application filed May 25, 1918. Serial No. 236,458.

To all whom it may concern:

Be it known that I, WILLIAM J. SMITH, a citizen of the United States, residing at Waterbury, in the county of New Haven and State of Connecticut, have invented a new and useful Improvement in Alarm-Clocks; and I do hereby declare the following, when taken in connection with the accompanying drawings and the characters 10 of reference marked thereon, to be a full, clear, and exact description of the same, and which said drawings constitute part of this application, and represent, in—

Figure 1 a view partly in front elevation and partly in vertical section of an alarm-clock constructed in accordance with my invention, with a portion of the dial and case broken away.

Fig. 2 a detached perspective view showing the alarm-set spring, the alarm shut-off lever, and the hammer-stop wire, in the positions they occupy when the alarm is shut off.

My invention relates to an improved 25 alarm-clock of the type commonly designated in the trade as "nickel alarms", the object being to provide an alarm-clock of the character described, with simple and reliable means whereby the alarm may be 30 manually shut off after it has begun ringing, and whereby it is automatically reset.

With these ends in view, my invention consists in an alarm-clock having certain 35 details of construction and combinations of parts as will be hereinafter described and pointed out in the claim.

In carrying out my invention as herein shown, I employ a finger-button 2 located within the bow or ring 3 and secured to 40 the upper end of a shut-off plunger 4 passing through the pendant 5 mounted in the sheet-metal clock case 6. A helical spring 7 located within a recess 8 in the upper end of the pendant provides for normally maintaining the said plunger in its elevated position. The lower end of the plunger is formed with an enlargement 9 the upper edge of which engages with the inner end of the pendant and limits the outward movement of the plunger under the action of 50 the spring 7. The lower end of the said enlargement 9 of the plunger engages with the upper face of an arm 10 bent inward at a right angle from the upper edge of an alarm shut-off lever 11 mounted upon a

staff 12 the forward end of which is journaled in the front movement-plate 13 and the rear end of which is journaled in the rear movement plate which is not shown. A spring 14 encircling the said 60 staff is engaged at one end with the lever and exerts a constant effort to lift the same into its normal or unlocked position. The inner end of the said lever is formed with a depending locking-arm 15 the lower end 65 of which is furnished with a stop-finger 16 bent inward at a right angle in position to co-act with the hammer-stop wire 17 of the alarm train, the said wire being mounted as usual in an arbor 18 carrying 70 the verge 19 and the hammer-wire 20. The lower end of the locking-arm 15 is also formed with a hook 21 the beak of which engages with the lower edge of the bent inner end of the alarm-set spring 22 the bent 75 inner end of which is formed with a releasing offset 23, the said spring being otherwise of ordinary construction and being operated as usual by the action of an alarm-cam 24 carried by an alarm-cam wheel 25 80 and co-acting with a finger 26 projecting from a collet 27 on the alarm-set arbor 28, on which the wheel 25 is free to move laterally.

In the ordinary running of the clock, the 85 alarm shut-off lever 11 occupies the position shown by broken lines in Fig. 1. Now when the alarm is being sounded, it may be manually shut off by pressing the plunger downward by the application of the finger to its 90 button 2, whereby the lever 11 is depressed and its stop-finger 16 brought into engagement with the hammer-stop wire 17 for stopping the vibration of the hammer. At the same time, the beak of the locking-hook 21 is 95 engaged with the lower edge of the inwardly turned bent end of the alarm-set spring 22 at a point just inside of the offset 23 therein. This results in locking the alarm shut-off lever in its depressed position in which it 100 prevents the alarm from sounding as shown by full lines in Fig. 1. Now in the due operation of the time-train, the alarm-cam 24 forces the wheel 25 inward and with it the spring 22, whereby the beak of the hook 21 105 is brought into registration with the offset 23 of the spring 22, thus releasing the alarm shut-off lever 11 to the action of its spring 14 by which it is lifted into its unlocked position in which it is shown by broken lines in 110

Fig. 1. This automatic release of the lever 11 will ordinarily take place within an hour or two after the alarm has been sounded. When the lever is lifted by the action of its spring 14, its locking-hook 21 is cleared from the alarm-set spring 22 as well as from the hammer-stop wire 17, but meanwhile the spring 22 having been pushed backward by the alarm-cam 24 for releasing the lever 11 to the action of its spring 14, has brought its inner end into position to co-act with the stop-wire 17 so that before the lever 11 is released by the spring 22, the same has already been brought into position to co-act with the stop wire 17 in preventing the sounding of the alarm. In a sense, therefore, when the lever 11 is lifted, the restraint of the alarm-train is shifted from the stop-hook 21 to the inner end of the lever 22. Of course the plunger might be replaced by any other manually operable shut-off member.

I claim:

In an alarm clock, the combination with the pendant thereof, of a manually operable shut-off plunger mounted therein, a pivotal alarm shut-off lever positioned to be operated by the said plunger and formed with a depending locking-arm the lower end of which is furnished with a stop-finger and

with a hook, a hammer-stop wire engaging 30 with the said stop-finger to shut off the alarm, an alarm-set spring having its free end inwardly bent for co-action with the said hammer-stop wire and also offset for co-action with the said hook which engages 35 with the said spring at a point close to the offset thereof, and an alarm-cam for operating the said spring, whereby when the said plunger is operated, the said lever is depressed for the engagement of its stop-finger 40 with the hammer-stop wire for shutting off the alarm, the hook of the lever being concurrently engaged with the alarm-set spring at a point close to the offset thereof so that when the spring is operated by the alarm-cam the hook, and hence the lever, is released, after which the said spring engages 45 with the said stop-wire to prevent the sounding of the alarm until the said spring is again released by the said cam.

In testimony whereof, I have signed this specification in the presence of two subscribing witnesses.

WILLIAM J. SMITH.
